UNITED STATES PATENT OFFICE.

HIRAM D. CROFT, OF SPRINGFIELD, MASSACHUSETTS, ASSIGNOR TO PERKINS MACHINE AND GEAR COMPANY, OF SPRINGFIELD, MASSACHUSETTS, A CORPORATION OF MASSACHUSETTS.

BROACH MECHANISM.

Application filed March 31, 1927. Serial No. 179,960.

My invention relates to improvements in mechanisms for automatically changing the positions of reciprocating broaches, and consists generally of certain peculiarly constructed broaches, means for holding said broaches in such a manner that they can be projected alternately into and out of operative position or the cutting field, means for attaching said first-named means to a reciprocating member, and means automatically to shift said broaches in said first-named means each time said member approaches either end of its travel, together with such other parts and members as may be necessary or desirable in order to render the mechanism complete and serviceable in every respect, all as hereinafter set forth.

The primary object of my invention is to provide a comparatively simple, yet strong, durable, and highly efficient, mechanism for automatically moving alternately two broaches or two lines of broaches, in the direction of their breadth, to locate them one at a time in broaching position or the cutting field, to the end that the cutting or broaching operation is practically continuous, that is to say, when the two broaches or two lines of broaches descend one of them makes a cut, and when they ascend the other makes a cut, and the operation of broaching is thereby materially accelerated, and the production of the machine equipped with my mechanism correspondingly increased.

Another object is to produce a mechanism of this character which is positive and accurate in its operation.

Other objects and advantages will appear in the course of the following description.

This mechanism is designed to be incorporated with broaching machines of the type disclosed in Letters Patent of the United States, No. 1,642,593.

I attain the objects and secure the advantages of my invention by the mechanism illustrated in the accompanying drawings, in which—

Figure 1 is a top plan of broach mechanism which embodies a practical form of my invention, showing the same in connection with the closely associated parts and members of a broaching machine, and with certain portions broken away; Fig. 2, a cross section through portions of said mechanism and said parts and members, taken on

lines 2—2, looking down, in Fig. 4; Fig. 3, 55 a left-hand side elevation of said mechanism and said parts and members with portions broken out and broken away; Fig. 4, a front elevation of said mechanism, or enough of the same to show its disposition when the 60 broaches are at the upper end of their travel; Fig. 5, a similar view showing the disposition of said mechanism when said broaches are at the lower end of their travel, and, Fig. 6, a side elevation of one of the 65 broaches.

Similar reference characters designate similar parts throughout the several views.

The old parts and members shown in connection herewith as necessary for a complete 70 understanding of the present invention comprise a column 1, a ram 3 arranged to reciprocate vertically on said column, and provided on one side with a rack 4, and a pinion 5 intermeshing with said rack, said pinion 75 being mounted on a shaft 6. From any suitable source of motive power the shaft 6 is caused to rotate, and, through the medium of the pinion 5 and the rack 4, to actuate the ram 3 on the column 1. Reversing mechanism for the shaft 6, and mechanism to bring about the operation of said reversing mechanism each time the ram arrives at either end of its travel, are required, but these are not shown because the nature 85 of the same is well understood. In this connection, however, reference may be had to said patent.

Broaches such as are used in this art are usually made in sections arranged end to 90 end, and I have here shown two lines of broaches of this character at 7 and 8, respectively, the former being at the left and the latter at the right. The broaches 7 cut on the down stroke and the broaches 8 cut on 95 the upstroke. The central longitudinal plane of the serrated part of each of the broaches 7 and 8 is at an angle of 45° to the main or body part of the broach, indicated by the numeral 9. When the broaches are 100 in place the bodies 9 of the broaches 7 and the bodies 9 of the broaches 8 are disposed at an angle of 90° to each other. Extending transversely through the body 9 of each of the broaches 7 and 8 are two, more or 105 less, pins 10 which project beyond both sides of said body.

The ram 3 is provided on the front side

with a holder made up of an interior or intermediate member 11, outer or enclosing members 11^a and 11^b, and plates 12—12. Secured by screws or other means to the face 5 of the ram 3, in the longitudinal center thereof, is the member 11 shaped in cross section substantially as shown in Fig. 2, and secured by bolts or other means to said face outside of said member and spaced 10 therefrom are the two members 11^a and 11^b shaped in cross section also substantially as shown in said view. The members 11^a and 11^b are similar in shape to each other except that the first is a left-hand element 15 and the second a right-hand element. This holder which in great part consists of the members 11, 11^a, and 11^b, has in the front side thereof, in the center, a vertical passage 13, and behind said passage vertical passages 14—14 arranged at an angle of 90° to each other, except at the rear ends where 20 said last-named passages extend rearwardly through the back side of the holder to the face of the ram. The plates 12 are secured 25 by bolts or otherwise to the top and bottom of the holder-forming members 11, 11^a, and 11^b. The plates 12, in the present example, are bolted to all three of the members 11, 11^a, and 11^b, and so assist in securing said 30 members in place.

A transverse slot 15 is formed in the face of the ram 3, with the bottom of said slot on a level with the top of the holder. Bolted or otherwise secured to the front 35 side of the ram above the slot 15, but extending a short distance below the top edge of the same, is a bar 16.

Mounted for longitudinal movement in the 40 passages or openings 14 in the holder are two carriers 17 having their rear or inner edges shaped to fit the corresponding parts of said openings, and extending upwardly to provide posts 18—18 on the back side of each of which at the top is mounted 45 a roll 19. In each carrier 17 is a vertical slot 20 that opens through the forward edge of said carrier, and in both sides of said carrier are diametrically-opposite slots 21. Each slot 21 consists of outer and inner 50 branches which are in parallel planes, and an oblique connection, substantially as shown in Fig. 6. The slots 20 are of a size and shape to receive the bodies 9 of the broaches 7 and 8, and the slots 21 are of a 55 size and shape to receive the protruding terminals of the pins 10 and permit the same to move between the ends of said last-named slots. The posts 18 extend upwardly 60 through suitable openings in the top plate 14, in front of the slot 15, in the ram 3.

The plates 12 hold the carriers 17 against 65 independent endwise movement in the holder. The serrated parts of the broaches 7 and 8 operate in and out of the passage 13, either set of said broaches when ad-

vanced being located with the teeth projecting from said passage beyond the front side of the holder.

Obviously, if either carrier 17 be forced downwardly from its high position in the 70 holder, the broaches in said carrier, being held against endwise movement by the plates 12, must be actuated outwardly by the action on the pins 10 of the inclined edges of the 75 grooves 21 in said carrier, and, if said carrier be actuated upwardly from its low position, said broaches must be drawn inwardly by the same means. When either carrier 17 is in its low position, the pins 10 are in the upper-end positions of the carrier slots 80 21, and, when said carrier is in its high position, said pins are in the lower-end portions of said slots. Since these end portions of the slots 21 are in parallel planes, the pins 10 are in the same plane, and the broaches 85 are held securely against either outward or inward movement.

An upright 22 is located at the left of the 90 ram 3, and has at the top a lip 23 that is secured by bolts or other means to the column 1 or other fixed part of the frame of the machine, and is secured in a similar manner at the bottom to a fixed part 24 of said frame. Secured by screws or other means to the front side of the upright 22, adjacent 95 to the top and bottom ends thereof, are upper and under cam plates 25 and 26, respectively, said cam plates having their adjacent edges inclined and parallel with each other, but the lower cam plate is located 100 farther to the left than is the upper cam plate.

A horizontal, movable cam plate 27 is 105 slidably arranged in the slot 15, with the upper and under edge portions of said plate behind the bar 16 and the upper plate 12, respectively, and extends to the left beyond the corresponding sides of the ram 3 and holder. The movable cam plate 27 is provided at its outer terminal, behind, with a 110 roll 28 in the paths of which the fixed cam plates 25 and 26 are located. In the cam plate 27 is a cam groove 29 in which are located the rolls 19. The intermediate and end portions of the cam groove 29 are in 115 parallel planes, and such portions are connected by portions which extend divergently upwardly from the intermediate portion.

The parts are so proportioned that, when 120 the cam plate 27 is moved to the right, the right-hand roll 19 is forced downwardly and the left-hand roll 19 upwardly, thereby forcing the right-hand carrier 17 downwardly and advancing the broaches 8, and forcing the left-hand carrier 17 upwardly and re- 125 tracting the broaches 7. Movement of the cam plate 27 in the opposite direction, or to the left, reverses the movements of the carriers 17 and the broaches 7 and 8. After 130 the carriers 17 have been actuated or shifted,

they are held securely in place by the rolls 19, one of which is then in one of the horizontal terminals of the cam groove 29 and the other in the intermediate horizontal portion of said groove.

Starting with the parts disposed as in Figs. 1, 3, and 4, the operation of this mechanism as a whole is described as follows:

The broaches 7 are carried down through the cutting field, by the ram 3 when it descends, and make their cut. As the ram approaches the lower end of its travel, and after the cut is made, the roll 28 encounters the fixed cam plate 26 and is thereby actuated inwardly, carrying with it the cam plate 27. As the cam plate 27 moves inwardly or to the right, the right-hand carrier 17 is forced downwardly and the left-hand carrier 17 is forced upwardly, through the medium of the rolls 19 in the cam slot 29, and the posts 18. The downward movement of the right-hand carrier 17 causes the broaches 8 to be advanced into the cutting field, through the medium of the pins 10 which extend from said broaches into the cam slots 21 in said carrier, and the left-hand carrier 17 causes the broaches 7 to be retracted or withdrawn from said cutting field. The broaches 7 and 8, which previously were disposed as shown in Figs. 1, 2, 3, and 4, are now disposed as shown in Fig. 5. The roll 28 is now against the right-hand edge of the fixed cam plate 26.

Next the ram 3 ascends, causing the broaches 8 to make their cut, until, as said ram approaches the upper end of its travel, the roll 28 encounters the fixed cam plate 25 and is actuated outwardly or to the left, carrying with it the cam plate 27. The cam plate 27, in moving outwardly again, reverses the positions of the rolls 19, so that the left-hand carrier 17 is forced downwardly and the right-hand carrier 17 is forced upwardly. The downward movement of the left-hand carrier 17 advances or projects the broaches 7 into the cutting field again, and the upward movement of the right-hand carrier 17 retracts from said field the broaches 8. The roll 28 is now against the left-hand edge of the cam plate 25.

Upon the succeeding downward and upward movements of the ram 3 the cycle of operation of the mechanism is repeated, and so on indefinitely.

The broaches 7 and 8, in being moved into and out of the cutting field, intersect each other's paths of travel to an extent which enables either set of broaches to be located with the central vertical plane of its teeth in the vertical plane of the holder for the carriers 17, which plane is also the central vertical plane of the cutting field.

More or less change in the shape, size, construction, and arrangement of some or all of the parts of this mechanism may be

made, without departing from the spirit of my invention or exceeding the scope of what is claimed.

What I claim as my invention, and desire to secure by Letters Patent, is—

1. In mechanism of the class described, a holder, broaches in said holder, and means alternately to retract and advance said broaches, in straight courses between parallel planes at the top and bottom of said broaches, out of and into the cutting field.

2. In mechanism of the class described, a holder, broaches arranged in angular relationship to each other in said holder, and means alternately to retract and advance said broaches, in straight courses between parallel planes at the top and bottom of said broaches from and into the cutting field.

3. In mechanism of the class described, a holder, broaches arranged in relative angular relationship in said holder, and means to retract and advance said broaches alternately, in straight courses between parallel planes at the top and bottom of said broaches, and cause them to intersect each other's paths of movement.

4. In mechanism of the class described, a holder, broaches arranged in relative angular relationship in said holder, and intermittently operating means simultaneously to retract and advance said broaches in straight courses between parallel planes at the top and bottom of the broaches.

5. In mechanism of the class described, a holder, broaches arranged in relative angular relationship in said holder, and intermittently operating means simultaneously to retract and advance said broaches, in straight courses between parallel planes at the top and bottom of the broaches, and cause them alternately to intersect each other's paths of travel.

6. In mechanism of the class described, a reciprocating member provided with a holder, broaches arranged in relative angular relationship in said holder, and means to retract one of said broaches and advance the other when said member approaches one end of its travel, and to reverse the relative movement of said broaches when said member approaches the other end of its travel, said broaches moving in straight courses between parallel planes at the top and bottom thereof.

7. The combination, in mechanism of the class described, with a reciprocating member provided with a holder, and broach carriers in said holder, of means to actuate said carriers longitudinally in said holder in opposite directions each time said member approaches either end of its travel.

8. In mechanism of the class described, a holder, carriers slidingly arranged lengthwise in said holder, and having cam slots therein, broaches slidingly arranged in said

carriers, between parallel planes at the top and bottom of said broaches, and provided with pins which extend into said cam slots, and means to actuate said carriers and thereby move said broaches into and out of the cutting field.

9. In mechanism, of the class described, a holder, carriers slidingly arranged lengthwise in said holder, and having cam slots therein broaches slidingly arranged in said carriers, between parallel planes at the top and bottom of said broaches, and provided with pins which extend into said slots, and means to actuate said carriers in opposite directions and thereby move said broaches alternately into and out of the cutting field.

10. The combination, in mechanism of the class described, with a reciprocating member provided with a holder, and fixed cam plates, of a movable cam plate carried by said member, and having a projection into the path of which said fixed cam plates extend, carriers arranged to slide up and down

in said holder, having cam slots in their sides, and provided with projections that extend into engaging relationship with said movable cam plate, and broaches arranged to slide in said carriers, between parallel planes at the top and bottom of said broaches, and provided with pins which project into said cam slots, whereby the movement of said movable cam plate in either direction causes said carriers to be actuated in opposite directions, and said broach to be advanced and retracted, according to the directions of the relative movements of said carriers.

11. In mechanism of the class described, a holder, carriers arranged for longitudinal movement in said holder, means to move said carriers in said holder, broaches movable in said holder, in straight courses between parallel planes at the top and bottom of said broaches, into and out of the cutting field, and means to advance and retract said broaches when said holder is actuated.

HIRAM D. CROFT.
